JOHN A. MULHALL, OF NEW YORK, N. Y., ASSIGNOR TO UNDERWOOD TYPEWRITER COMPANY, OF NEW YORK, N. Y., A CORPORATION OF DELAWARE.

COIN-CONTROLLED TYPE-WRITING MACHINE, &c.

1,197,757.

Specification of Letters Patent. Patented Sept. 12, 1916.

Application filed August 25, 1910. Serial No. 578,821.

To all whom it may concern:

Be it known that I, JOHN A. MULHALL, a citizen of the United States, residing in New York city, in the county of New York and 5 State of New York, have invented certain new and useful Improvements in Coin-Controlled Type-Writing Machines, &c., of which the following is a specification.

The present invention relates to a coin-controlled mechanism attached to or forming part of, or adapted to be arranged in connection with a typewriting or other manipulable machine, and serving to restrict the use of such machine to definite lengths 10 or periods of time predetermined in accordance with the value of the coin, but capable of being rendered operative for a predetermined period of time whenever a coin of the proper size and weight is deposited in 15 the apparatus.

One object of the present invention is to produce a machine of the class specified, which is inoperative except upon deposit of coins of the proper weight and material. 20 Heretofore the machines have commonly been responsive to all sorts of spurious coins and devices, the only requisite seeming to be that the deposited article be of proper size and of sufficient rigidity to serve as a temporary link in the mechanism. Often the construction of the apparatus has been such as to permit of the passage of card board and other semi-rigid material to interlocking 25 position with the gears or levers, with the result that when the gearing was actuated such material has been crumpled or folded, so as to clog the mechanism and to put the entire apparatus out of commission. In the present invention, on the other hand, 30 it is absolutely impossible for pieces of card board or other light material to become interlocked with the gearing. Such material cannot enter into the mechanism at all. Furthermore, slugs of steel and metal counterfeits are weeded out, and discarded into the box, before they can reach an operative 35 position with respect to the gearing.

Another object of the invention is to so construct the coin operated apparatus or interponent mechanism that the machine controlled thereby is inoperative until after the coin has actually performed its function and is discharged into the coin receptacle. In the prior art the coin controlled apparatus

renders the machine operative before the 55 coin has been released from the driving mechanism; and consequently it has often been possible, after the machine has been set into operation, to lock the gearing by some device, so that, without the use of other 60 coins, the machine might thereafter be used indefinitely. It is impossible in the present invention for a single coin to be made to operate the machine beyond the proper and predetermined time limit. 65

A third object of the invention is to utilize each operation of the coin controlled apparatus to wind the clock or time mechanism which determines the time of operation of the machine. In other words, each time a 70 coin is deposited and the gearing actuated to place the machine in operation, the clock is simultaneously wound for the period of operation of the machine. The time mechanism does not operate except when the machine is operative. The ordinary more or less elaborate clock mechanism is therefore in the present invention, unnecessary. An extremely simple and inexpensive clock mechanism is quite sufficient for the run permitted for a single coin. Heretofore it has been customary to install as part of the apparatus a clock of the usual type, the same to be run continuously whether the machine was in operation or not. The continual 75 operation of the clock naturally involved periodical winding thereof by some person having access to the mechanism; and this in turn has involved a large amount of labor and expense, all of which is entirely eliminated in the present invention. The time mechanism of this invention in addition 80 therefore to being simple and inexpensive, requires absolutely no attention. 85

Other objects and features of this invention will presently appear on reference to the accompanying drawings in which

Figure 1 is a perspective view of the assembled coin and time controlled apparatus attached to a typewriter frame and controlling the lock bar of the typewriter, the casing of the apparatus being partly broken away to show the mechanism; Fig. 2 is a view in side elevation of the assembled mechanism in its normal or locking position, the 100 side of the casing being removed to show the parts; Fig. 3 is a top plan view of the mechanism taken on the line 3—3 of Fig. 2; 105

Fig. 4 is a view similar to Fig. 2 except that the parts are here shown in the position assumed at the instant the typewriter lock bar is released; Fig. 5 is a top plan view showing the coin receiving tray and the chutes by which the coin is guided; Fig. 6 is a detail view in side elevation of the levers which are interlocked by the coin to operate the mechanism; Fig. 7 is a detail view in perspective to show the bearings and supports for the levers of Fig. 6; Fig. 8 is a detail view showing the positions of the levers of Fig. 6 with respect to a release latch before the discharge of the coin; Fig. 9 is a view similar to Fig. 8 showing the position of the parts upon the discharge of the coin. Fig. 10 is a sectional view of some of the parts seen in Fig. 7.

Referring to the drawings, the coin controlled apparatus is provided with webs or lugs 82 by means of which it may be attached to a typewriter frame or other machine. The type key levers 1 of the typewriting machine are shown with the usual hooks 2 to engage the stop bar 3. The bar 3 forms part of a line locking mechanism of the typewriter to lock the type keys automatically at the completion of each line of writing in a well known manner. In the present invention the bar 3 continues to perform its usual function of locking the keys at the end of the line, but in addition has the function of locking the keys to maintain the typewriter inoperative except for the periods for which the coins are deposited. The bar is supported on a pair of arms 5, one only of which is shown in the drawings, the other being at the other end of the typewriting machine. The arms 5 are fast to a shaft 6 which has bearing at either end in the frame of the typewriting machine. To maintain the typewriting machine normally inoperative, the bar is held in locking position under the hooks 2 by means of a bent or offset arm 7 forming part of a shaft 8 having bearings in the casing 10 of the coin controlled mechanism.

Normally the arms 5 with the bar 3, and the locking arm 7 are all in the position shown in dotted lines in Fig. 2, wherein it will be noted that the bar is engaged by hooks 2 on key levers to prevent operation of the latter. When the mechanism is operated, however, upon deposit of a coin, the arm 7 moves to the position shown in Fig. 4, permitting the lever 5 and bar 3 to move under the action of a spring 9 also to the position shown in Fig. 4, whereupon the key levers 1 may be operated. Although at the end of the lines the bar 3 returns to its Fig. 2 position to perform its usual function of locking the keys, the locking arm 7 is nevertheless retained in its Fig. 4 position so long as the machine remains operative by reason of the deposit of a coin. In

other words, the locking arm 7 does not return to the Fig. 2 position with the locking bar at the end of each line, but only at the expiration of the time limit for which the machine has been rendered operative.

The coin operated mechanism or interponent mechanism which controls the locking arm 7 will now be described. Mounted to move in a pocket or slot 11 in the top of the frame 10 is an oblong rectangular slide 12 carrying a finger-piece or handle 13' by means of which the slide may be moved. Through the slide 12 is an opening 13 of a size to permit of the passage of the coin. From the outside of the casing to the pocket 11 is also a hole or passage 14 of similar size. In the normal or Fig. 4 position of the slide the two openings register so that the slide may receive the coin. The slide has sufficient movement in the frame, to permit the opening 13 in the slide to register with a second opening 15 from the pocket to the interior of the casing. A spring 16 attached at one end to a pin 17 protruding from the finger-piece 13' into the interior of the casing, and attached at the other end at 18 to the casing normally holds the slide 12 in the position shown in Fig. 4. Suitable slots 19 and 20 in the pocket walls of the casing permit of the movement of the finger-piece and pin 17 with the slide. The throw or movement of the slide is limited by the end walls of the pocket 11.

Pivoted at 21 immediately below the top of the casing is a lever 22. This lever carries at one end a coin tray 23 immediately below the opening 15 to the interior of the casing. A counterweight 24 at the other end of the lever 22 normally holds the lever in the full line position of Fig. 2. The counterweight is such, however, that when a coin of proper weight is moved by the slide 12 so as to fall into the tray 23, the lever 22 with coin tray will swing from the full line to the dotted line position of Fig. 2. Contact of the counterweight 24 with the roof of the casing or with other suitable stop, determines the extent of movement of the coin tray when the latter is swung by a coin. A plate 25 projects sufficiently below the roof of the casing to hold the coin on the tray until the latter has reached its coin discharging position.

Attached to the side wall of the casing is a chute 26, the upper end of which registers with the coin discharging throat of the coin tray so as to receive the coin from the tray when the latter is in the position shown in dotted lines in Fig. 2. In alignment with the chute 26, but separated therefrom by a space 27, is a chute 28 also attached to the wall of the casing. The chute 28 discharges against a chute 29, and the two together form at one end a throat or guide for the coin to the interlocking levers which con-

trol the mechanism. The space 27 between the chutes 26 and 28 is of greater width than the diameter of the coin. A permanent magnet 30, secured to the framework of the machine, has its poles turned toward the opening 27, and is sufficiently close to the chutes to divert any steel or similar slugs or coins of improper material. Slugs so diverted from the chutes fall to the bottom of the casing, and are ineffective to operate the machine. Slugs of improper weight also fall through opening 27. Such slugs are usually lighter than the proper slugs or coins, and do not, therefore, acquire impetus sufficient to carry them across the gap 27.

The coin on leaving the chute 29 slides over the front face of a lever 31 and comes to rest on a lug or seat 32 on this lever. The lever 31 is fast to a shaft 33 which is mounted in the side walls of the casing, and which at one end projects through the casing to carry a crank or handle 34, by means of which the shaft may be turned.

Loosely mounted on the shaft 33 is a sleeve 35 having fast thereto a block 36. In the sides of the block 36 are slots 37, and pivoted at 38 and 39 to the block to have lateral movement in the slots 37, are arms 40 and 41. The arms 40 and 41 together with the ears 45 grasp and hold the coin. A coil compression spring 42 engaging at one end the arm 40 and at the other end the arm 41, extends through the block and holds these arms normally in the position shown in Figs. 1 and 3. The arms are, however, free to be moved around in their pivots against the tension of spring 42 so that the ends of the arms may be separated as shown in Fig. 9. The swing of the levers 40 and 41 on their pivots 38 and 39, is limited in each direction by contact of the arms with the inside walls of the slots 37. The arms 40 and 41 coöperate with the lever 31 and move with that lever when a coin is on the seat 32 and the handle 34 is turned. The diameter of the coin is such that when it rests on its seat on the arm 31, it is engaged by grooves in the opposing ears or lugs 45 on the arms 40 and 41 thus interlocking the latter arms with the lever 31, so that all move together when the crank 34 is turned counter-clockwise from the position shown in Fig. 2 to the position shown in Fig. 4. The width of the lever 31 is such, however, as to permit it to pass freely between the arms 40 and 41 when no coin rests on the seat 32. Also fast to the sleeve 35 is a sector 43, which meshes with a pinion 44 loosely mounted on a fixed shaft 89. The sector 43 and the pinion 44 constitute a winder for the clock mechanism. The pinion 44 is in the clock train and when rotated by the sector 43, winds the clock spring. The clock train is shown in dotted lines in Fig. 2. In the present invention the clock operates only when the typewriter is

operative; and the clock train is normally locked by the locking device or latch 48 having a detent 49, adapted to enter a slot or recess in a disk 50 connected to the first wheel 93 of the clock train by means of the hub 100. As long as the detent is in the recess, therefore, the clock cannot go. When a coin is in place on the seat 32 so as to lock the arms 40 and 41 to the lever 31, then when the crank 34 is turned, the sleeve 35 turns, carrying with it the sector 43. After a movement of the crank 34 and sector 43 sufficient to wind the clock spring, the latch 48 is disengaged from the disk 50 in the following manner. The latch lever 48 is pivotally mounted or fulcrumed on a shaft or stud 52. It carries a wrist pin 53. Fast to the sleeve 35 is a cam member 54 which after sufficient counterclockwise movement of the shaft 35 with the crank 34, engages the wrist pin 53 and rocks the lever 48 against the tension of a spring 55 from the position shown in Fig. 2 to the position shown in Fig. 4. In the latter position, the detent 49 is disengaged from the disk 50; and the wheel 93 with the disk 50 is then free to be driven clockwise by the clock spring. The cam 54 does not disengage the locking lever 48 from the disk 50 until after a sufficient movement of the sector 43 to wind the clock.

On the forward end of the lever 48 is a wrist pin 56 engaging a lever or arm 57 fast to the shaft 8 which, it will be remembered, carries the bar locking arm 7. A spring 58 tends to turn the shaft 8 and arm 57 in such a manner as to withdraw the arm 7 from the locking lever 5. These parts are prevented from so moving, however, by an arm or latch 59 also fast to the shaft 8 and forming with said shaft 8 and arm 7 a bell crank lever. The arm 59 carries at its upper end a detent or lug 60 which engages a shoulder on a lever 61 pivoted at 62 to the frame of the machine. Until the lever 61 is rocked on its pivot, as presently to be described, it holds the arm 60 from clockwise movement, and therefore prevents movement of the shaft 8 and arm 57 by the spring 58, even though the lever 48 be withdrawn from the arm 57.

Pivoted to a stud 63 carried on the frame of the machine is a lever having two arms 64 and 65 respectively. This lever is normally held in the position shown in Fig. 2 by means of a spring 66 attached at one end to the arm 65 of the lever and at the other end to a pin 67 on a bracket 68. The end of the arm 64 normally lies in the path of the coin when the latter rests upon the seat 32 on lever 31, and is swung forward counterclockwise by the movement of the shaft 33. This movement of the coin with the lever 31, as has been pointed out, also effects a similar movement of the arms 40 and 41. When the lever 31 brings the coin into en-

gagement with the lever arm 64, the latter is rocked as shown in Fig. 4 against the tension of the spring 66, and simultaneously, the lever arm 65 is forced forward between the advancing arms 40 and 41. The end of the arm 65 is beveled on either side to form a wedge or spear head (see Figs. 1 and 3). The inclined sides or cam surfaces of the wedge engage the opposing faces of the arms 40 and 41, and the latter are thus turned on their pivots 39 and 38, against the tension of the spring 42. The turning of the arms 40 and 41 cause the same to separate a distance sufficient to permit of the release of the coin (see Fig. 9).

Pivoted at 69 on the bracket 68 is a bell crank lever comprising lever arms 70 and 71. The arm 70 rests upon the end of the lever 61 which controls the arm 59 heretofore mentioned. Arm 70 normally lies in the position shown in Fig. 1, but it may be depressed so as to rock the lever 61 against the tension of spring 72, and so disengage lever 61 from arm 59. Arm 59 is therefore released when arm 71 of the bell crank lever is moved to the left. The arm 71 is normally directly in front of the arm 41, as shown in Fig. 8. When, however, the arm 41 in advancing is turned on its pivot 38 by reason of its engagement with the wedge 65, it is moved laterally with respect to the lever arm 71, as indicated in Fig. 9. It is in this position at the instant the coin is released. Upon release of the coin the spring 42 snaps the arms 40 and 41 toward each other, and in so doing, causes the end 73 of the arm 41 to strike the lever arm 71, whereupon arm 70 and lever 61 are rocked to release the locking arm 59. When the arm 59 is released by the arm 61, the spring 58 turns the shaft 8 and bar locking arm 7 until the arm 57 is stopped by the wrist pin 56 on the clock controlling lever 48, which latter has previously been moved to Fig. 4 position by the cam 54 to permit of the action. The movement of the arm 7 permits the bar supporting arm 5 to be moved by its spring to remove the bar 3 from the key lever hooks 2. The machine is then operative. The operative condition of the machine is announced by the bell 75, which is struck by the clapper 76 carried by the latch arm 59. The movement of the arm 59 when released brings the clapper to the bell, as shown in Fig. 4.

At the time of the release the parts are in the position shown in Fig. 4. The operating crank 34 has been swung with the parts mentioned from its initial position until stopped by a stop pin 77 projecting from the outside wall of the casing. The lever 41 is holding the lever 70, 71, and with it the lever 61, in such position as to permit free movement of the latch lever 59. The lever 48 with detent 49 is out of contact

with the disk 50, and the clock is in operation.

A coil spring 78 attached to the shaft 33 then moves the shaft with the lever 31 and crank 34 back to initial position, where the movement of these parts is arrested by a stop pin 80 which projects from the outside of the casing into the path of the crank. All the parts attached to the sleeve 35 including the levers 40 and 41, and the cam 54 are slowly returned to initial position by the sector 43 which is now being driven by the clockwork. During this time the disk 50 is being revolved to bring the recess in the same again to the detent 49 of the latch lever 48. When the return movement of the sleeve 35 has progressed far enough to remove the arm 41 from the lever 70, the lever 61 under action of the spring 72 is pressed against the top of locking arm 59 so as to be ready to latch the same in initial position at the proper time. Similarly, after a slight return movement of the cam 54, the detent 49 is forced by the spring 55 against the disk 50 so as to be ready to engage the recess in the latter when the same is presented to it. The spring 55 is stronger than the spring 58 which bears on the arm 57, and consequently the arm 57 with shaft 8 and arms 59 and 7, is gradually returned to initial position as the cam 54 releases latch lever 48 to spring 55. At the expiration of the time limit for which the machine is operative, the detent 49 drops into the recess in the disk, and this final movement brings the bar 3 under the hooks 2 and brings the locking arm 59 to latching position. Spring 72 operates the latch lever, and as the latch lever drops to final position, a clapper 81 carried thereby is thrown against the bell 75 announcing that the machine is again inoperative.

The coin receiving tray 23, and the counterweight 24, are of about equal weight, or at least the pivotal point 21, is so positioned that the lever 22 is about equally balanced; thus by tilting or shaking the machine, a method frequently resorted to, in order to set the mechanism in motion without the insertion of a coin, it will be evident that the lever 22 will rock freely on its pivot which might cause unnecessary wear to or derangement of these parts. In order to avoid this, a swinging detent 81^a is suspended from the casing and so arranged with respect to the lever 22, that when the machine is tilted or otherwise shaken, the detent will swing into the path of the counterweight 24, checking its upward movement and preventing the rocking of the lever 22.

In operation, a coin 82 is deposited in the coin slots 14, 13, Fig. 4, and rests upon the top of the casing 10. The handle 18 is pressed rearwardly from the position at Fig. 4 to that at Fig. 2. The coin is car-

ried back until it drops through the opening 13 in the top of the casing 10. The coin falls upon the tray 23, and tilts it downwardly from the full line to the dotted line 5 position at Fig. 2, until it rests upon the top of the chute 26. The coin slides down the inclined tray and off therefrom into said chute 26, and slides down the latter, gathering impetus, so that it can jump the gap 27 between the chute 26 and the small depressed chute 28. At the bottom of the latter may be placed a rifle 83 to check the motion of the coin. The latter rises over said rifle, and drops down the hopper, comprising the 10 member 29 and an apron 84 formed on the end of the lower chute 28. The coin is discharged by said hopper into the pocket comprising the upturned end of the lever 31, the lug 32 on said lever and the pair of arms 15 or jaws 40, 41 including the ears 45 thereon. The handle 85 is now grasped and crank 34 rotated thereby counterclockwise from the 20 position at Figs. 1 and 3 to the position at Fig. 6. This turns the shaft 33, which is 25 fixed to the crank, and also the arm 31. When no coin is carried by the arm 31, the latter will swing idly; but the introduced coin, as at Fig. 1, forms a connection between the arm 31 and the pair of jaws 40, 30 41, and enables the latter to be swung by 31 from the normal position at Fig. 2 to the position at Fig. 4. During this motion of the parts 40, 41, the block or head 36 is also rotated, together with the hollow shaft or 35 sleeve 35, and the rack or segment 43. The latter, of course, rotates the pinion 44 to wind the clock-driving spring 86; said pinion being secured by rivets 87 to a barrel 88 containing said spring and secured to one 40 end of the latter; said barrel and pinion turning upon the fixed horizontal shaft 89, to which the inner end of the spring 86 is secured by means of a pin 90. During this rotation of the spring barrel 88, a pawl 91, 45 mounted on said barrel, rides idly over the teeth of a ratchet wheel 92, which is fixed upon the side of a toothed wheel 93, which forms the first member of the train of clock 50 gearing, the latter also including members 94, 95, 96, 97 and 98 and the escapement wheel 45^a, with which coöperates the usual escapement 99, 46, 47; said clockwork devices being of the ordinary type. During this rotation of said pinion 44 and spring barrel 55 88, the gear 93 and the remainder of the clock train remain stationary; and the same is true of the latch wheel 50, which is fixed to said gear 93 by means of a hub 100, Fig. 3. The latch 49 remains in a recess 101 in 60 the latch wheel 50 during greater part of the movement of the crank 34, but by means of the swinging cam 54 (fixed on the sleeve 35) the latch arm 48 is swung, and the latch 49 withdrawn from the notch 101, thereby 65 releasing the latch wheel 50, so as to permit the clockwork to run. At the same time the locking pin 56 is withdrawn from the arm 57, so as to offer no obstacle to the movement of the arm 59, which releases the typewriter for operation, as will now be explained. Just before the crank 34 is arrested by the stop 77, the coin 82 is engaged by the arm 64 of the coin trip, and the double bevel arm 65 of said trip separates the jaws 40, 41 to about the position seen 75 at Fig. 9. The stroke of the crank 34 having thus been completed, the operator releases the handle 85, and the spring 78 returns the crank 34 to normal position together with the arm 31 fixed thereto; but 80 the gear 43 and the parts 36, 40, 41 and 54 do not accompany the crank 34 in its return movement. The arm 31 now being lifted from the coin 82, the latter drops as seen at Fig. 4 onto the floor of the casing, or into 85 any receptacle that may be provided for it. The spring 66 returns the coin-tripping lever 64, 65 to normal position, and the jaws 40, 41, being no longer held apart by 90 said coin-tripping lever, are pressed toward each other by the spring 42, and the end 73 of the jaw 41 strikes the arm 71 of lever 70, causing the latter to vibrate the latch 61 and release the arm 59; whereupon by means of spring 58, the rock-shaft 8 is rotated and 95 the locking arm 7 withdrawn from the key-locking lever 5, and the spring 9 moves the lever 5 backwardly to carry the horizontal locking bar 3 out of the paths of the hooks 2 on the key levers 1 of the typewriter, so 100 that the latter may be freely operated; its released condition being indicated by the stroke of the clapper 76 against the bell 75. The spring 86 in tending to unwind, operates through the pawl 91 and ratchet 92, 105 to drive the clockwork, and to carry the parts 44, 43, 35, 54, 36, etc., slowly back to normal positions. During the first part of such return movement, the notch 101 on the latch disk 50 moves past the latch 49, so 110 that the latter, when released by the cam 54, rides idly upon the periphery of the revolving disk 50. Said disk, which turns always in the same direction, is given a complete 115 revolution by reason of its connection with the wheel 93 of the clockwork, and when the notch 101 again arrives opposite the latch 49, the spring 55 snaps the latter into said notch, thus preventing further operation of the clockwork. At the same time, the arm 57 is thrown up by the pin 56, causing the shaft 8 to rock and the arm 7 to relock the typewriter keys. The spring 72 snaps the latch 61 down to latch the arm 59, and the 120 striking of the bell 75 by the clapper 81 announces that the machine is locked. The spring 86 is held from further unwinding by reason of the locking of the disk 50, which is fixed to the clock gear 93, that is 125 driven by said spring through the pawl 91. 130

This determines the normal positions of the parts 43, 35, etc.

Whereas I have described the improvements as used in connection with a typewriter, it is obvious that certain of them are adapted for use in connection with various other machines. It is also obvious that the structure shown is capable of considerable modification within the scope of the invention. Portions of the improvements may be used without others.

Having thus described my invention, I claim:

1. The combination in a coin control mechanism, of a device adapted to control the operation of some machine and normally holding such machine inoperative, and a clockwork, said coin control mechanism comprising an operating shaft, a lever fast on said shaft, levers loose on said shaft, said levers being provided with means whereby they may be locked together by a coin so as to move together when the shaft is rotated, and means whereby when the shaft is turned the clockwork is wound and one of the loose levers is made to release the machine controlling device.

2. The combination of a coin controlled mechanism, with a device controlling the operation of some other machine or apparatus and normally rendering such other apparatus inoperative, said coin controlled mechanism comprising two elements, the first of which elements is operative only when engaged by a suitable coin, and the second of which elements is actuated by the first to operate the device which controls the normally inoperative apparatus, and means for rendering the second of said two elements inoperative by the first until the coin is in a position where it can no longer be retained by the mechanism.

3. The combination of a coin controlled mechanism, with a device controlling the operation of some other machine or apparatus and normally rendering such other apparatus inoperative, said coin controlled mechanism comprising two elements, the first of which elements is operative only when engaged by a suitable coin, and the second of which elements is actuated by the first to operate the device which controls the normally inoperative apparatus, and means for rendering the second of said two elements inoperative by the first until the coin is discharged from the mechanism.

4. The combination with a machine having a locking means, of a device controlling the operation of said locking means and rendering the same normally inoperative, and a coin controlled mechanism comprising two elements, the first of which elements is operative only when engaged by a suitable coin, and the second of which elements is actuated

trols the normally inoperative apparatus, and means for rendering the second of said two elements inoperative by the first until the coin is in a position where it can no longer be retained by the mechanism.

5. The combination of a coin controlled mechanism, and a device controlling the operation of some other machine or apparatus and normally rendering such other apparatus inoperative, said coin controlled mechanism comprising two members which are operative only when engaged by a suitable coin, and a third element which when actuated operates the device which controls the normally inoperative apparatus, means for advancing said first two members with the coin toward said third element, and means for presently separating said first two members so as to release the coin and bring one of said separated elements into coöperative relation with said third element to operate the latter.

6. The combination of a coin controlled mechanism, and a device controlling the operation of some other machine or apparatus and normally rendering such other apparatus inoperative, said coin controlled mechanism comprising two members which are operative only when engaged by a suitable coin, and a third element which when actuated operates the device which controls the normally inoperative apparatus, means for advancing said first two members with the coin toward said third element, and a cam device in the path of the coin to be engaged by the latter to separate said first two members so as to release the coin and bring one of said separated elements into coöperative relation with said third element to operate the latter.

7. The combination of a coin controlled mechanism, and a device controlling the operation of some other machine or apparatus and normally rendering such other apparatus inoperative, said coin controlled mechanism comprising two levers sufficiently close to one another to be overlapped by a suitable coin so as to be moved together by said coin, one of said levers being also movable with respect to the other lever to vary the distance between the levers, a third element which when actuated operates the device which controls the normally inoperative apparatus, means acting on the coin when the latter overlaps the two levers to advance the two levers toward said third element, means which, as the levers advance together, engages the lever which is movable to vary the distance between the levers and by such engagement separates the levers, permitting the coin to fall between the same, and bringing the lever so engaged into position to act upon and operate said third element.

8. The combination of a coin controlled mechanism, and a device controlling the op-

- eration of some other machine or apparatus and normally rendering such other apparatus inoperative, said coin controlled mechanism comprising two levers sufficiently close to one another to be overlapped by a suitable coin so as to be moved together by said coin, one of said levers being also movable with respect to the other lever to vary the distance between the levers, a third element which when actuated operates the device which controls the normally inoperative apparatus, means acting on the coin when the latter overlaps the two levers to advance the two levers toward said third element, a cam device which, as the levers advance together, is engaged by the coin and caused to engage the lever which is movable to vary the distance between the levers and by such engagement separates the levers, permitting the coin to fall between the same, and bringing the lever so engaged into position to act upon and operate said third element.
9. The combination of a coin controlled mechanism, and a device controlling the operation of some other machine or apparatus and normally rendering such other apparatus inoperative, said coin controlled mechanism comprising two levers sufficiently close to one another to be overlapped by a suitable coin so as to be moved together by said coin, one of said levers being also movable with respect to the other lever to vary the distance between the levers, a third element which when actuated operates the device which controls the normally inoperative apparatus, means acting on the coin when the latter overlaps the two levers to advance the two levers toward said third element, means which as the levers advance together, engages the lever which is movable to vary the distance between the levers, and by such engagement separates the levers, permitting the coin to fall between the same, the lever so engaged having an extension which acts upon said third element after the lever has been moved to release the coin.
10. The combination with a clockwork, of a winder normally incapable of winding said clockwork, a coin-controlled device for rendering said winder capable of winding said clockwork, a lock normally restraining some other machine or apparatus from operation, and an obstructing member preventing the release of said lock and released by the actuation of said winder.
11. The combination with a clockwork, of a winder normally incapable of winding said clockwork, a coin-controlled device for rendering said winder capable of winding said clockwork, a lock normally restraining some other machine or apparatus from operation, an obstructing member preventing the release of said lock, and a spring normally tending to move said obstructing member and release said lock, said obstructing member being releasable by the actuation of said winder.
12. The combination with a clockwork, of a winder normally incapable of winding said clockwork, a coin-controlled device for rendering said winder capable of winding said clockwork, a lock normally restraining some other machine or apparatus from operation, an obstructing member preventing the release of said lock, a spring normally tending to move said obstructing member and release said lock, said obstructing member being releasable by the actuation of said winder, and a latch lever for securing said obstructing member in its locking position.
13. The combination with a clockwork, of a winder normally incapable of winding said clockwork, a coin-controlled device for rendering said winder capable of winding said clockwork, a lock normally restraining some other machine or apparatus from operation, an obstructing member preventing the release of said lock, a spring normally tending to move said obstructing member and release said lock, said obstructing member being releasable by the actuation of said winder, and a latch lever for securing said obstructing member in its locked position, said coin-controlled device acting to release said latch lever on the actuation of said winder.
14. The combination with a clockwork, of a winder normally incapable of winding said clockwork, a coin-controlled device for rendering said winder capable of winding said clockwork, a lock normally restraining some other machine or apparatus from operation, an obstructing member preventing the release of said lock, a spring normally tending to move said obstructing member and release said lock, said obstructing member being controllable by the actuation of said winder, and a latch lever for securing said obstructing member in its locked position, said coin-controlled device embodying normally operatively disconnected members connectible through the intermediary of a coin, some of said members being operatively connected to said winder, and adapted to manipulate said latch lever.
15. The combination with a clockwork, of a winder normally incapable of winding said clockwork, a coin-controlled device for rendering said winder capable of winding said clockwork, a lock normally restraining some other machine or apparatus from operation, a bell crank lever engaging said lock to operate the same, and a latch lever engaging said bell crank lever to secure said bell crank lever in a position corresponding to the locked condition of said lock, said latch lever being releasable by said coin-controlled device.
16. The combination with a clockwork,

- of a winder normally incapable of winding said clockwork, a coin-controlled device for rendering said winder capable of winding said clockwork, a lock normally restraining some other machine or apparatus from operation, a bell crank lever engaging said lock to operate the same, a latch lever engaging said bell crank lever to secure said bell crank lever in a position corresponding to the locked condition of said lock, said latch lever being releasable by said coin-controlled device, and a signal operated by said bell crank lever to denote the release of said bell crank lever by said latch lever.
17. The combination with a clockwork, of a winder normally incapable of winding said clockwork, a coin-controlled device for rendering said winder capable of winding said clockwork, a lock normally restraining some other machine or apparatus from operation, a bell crank lever engaging said lock to operate the same, and a latch lever engaging said bell crank lever to secure said bell crank lever in a position corresponding to the locked condition of said lock, said latch lever being releasable by said coin-controlled device, said coin-controlled device embodying a plurality of elements operatively disconnected from each other, and adapted to be operatively connected together by the interposition of a coin, one of said elements being movable relative to others of said elements, to release said coin.
18. The combination with a clockwork, of a winder normally incapable of winding said clockwork, a coin-controlled device for rendering said winder capable of winding said clockwork, a lock normally restraining some other machine or apparatus from operation, a bell crank lever engaging said lock to operate the same, and a latch lever engaging said bell crank lever to secure said bell crank lever in a position corresponding to the locked condition of said lock, said latch lever being releasable by said coin-controlled device, said coin-controlled device embodying a plurality of elements operatively disconnected from each other, and adapted to be operatively connected together by the interposition of a coin, one of said elements being movable relative to others of said elements, to release said coin and means for moving the said one of said elements relative to the others to release said coin during the movement of said winder.
19. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, and a bell crank lever having one arm engaging said lock and another arm engaging said latch whereby the movements of said latch and said lock may happen in proper sequence.
20. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen in proper order, and a connection between said winder and said latch, whereby the actuation of said winder will enable the movement of said latch and said lock.
21. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen in proper order, a connection between said winder and said latch, whereby the actuation of said winder will enable the movement of said latch and said lock, and a spring connected to said bell crank lever normally tending to release said lock.
22. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen in proper order, a connection between said winder and said latch, whereby the actuation of said winder will enable the movement of said latch and said lock, and a spring connected to said bell crank lever normally tending to release said lock and said latch, said coin-controlled device controlling the movement of said lever with the aid of said spring.
23. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and an-

- other arm engaging said latch, whereby the movement of said latch and said lock may happen in proper order, a connection between said winder and said latch, whereby the actuation of said winder will enable the movement of said latch and said lock, a spring connected to said bell crank lever normally tending to release said lock and said latch, and a latch lever for preventing the movement of said bell crank lever, said coin-controlled device acting to move said latch lever to release said bell crank lever.
24. The combination with a clockwork, of a winder normally restrained from winding the spring thereof, a coin controlled device for permitting said winder to wind said spring, a lock normally preventing the operation of some machine, a latch for restraining the movement of the clockwork, a bell crank lever having one arm engaging said lock and another arm engaging said latch, a connection between said winder and said latch whereby the actuation of the winder will cause movement of said latch and lock, a spring connected to said bell crank lever normally tending to release said latch and lock, a latch lever for preventing the movement of said bell crank lever, said coin controlled device including a pair of arms movable relative to each other to hold a coin, and said latch lever adapted to be actuated by one of said pair of arms after the release of the coin.
25. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen in proper order, a connection between said winder and said latch, whereby the actuation of said winder will enable the movement of said latch and said lock, a spring connected to said bell crank lever normally tending to release said lock and said latch, a latch lever for preventing the movement of said bell crank lever, said coin-controlled device acting to move said latch lever to release said bell crank lever, said coin-controlled device including a pair of arms movable relative to each other, a manually operated lever adapted to be connected to said pair of arms through the intermediary of a coin, and means for moving one of said arms relative to each other to release said coin after the release of said latch lever.
26. The combination with a clockwork, of a winder normally incapable of winding said clockwork, a coin-controlled device for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen in proper order, a connection between said winder and said latch, whereby the actuation of said winder will enable the movement of said latch and said lock, a spring connected to said bell crank lever normally tending to release said lock and said latch, a latch lever for preventing the movement of said bell crank lever, said coin-controlled device including a pair of arms movable relative to each other, a manually operated lever adapted to be connected to said pair of arms through the intermediary of a coin, and means for moving one of said arms relative to each other to release said coin after the release of said latch lever, said last-mentioned means being operable by the movement of said lever.
27. The combination with a clockwork, of a winder normally incapable of winding said clockwork, a coin-controlled device for rendering said winder capable of winding said clockwork, a lock normally restraining some other machine or apparatus from operation, and means connected to said winder for effecting the release of such other machine or apparatus, said coin-controlled device including a lever and a pair of arms movably mounted relative to said lever, and adapted to be operatively connected thereto through the intermediary of a coin.
28. The combination with a clockwork, of a winder normally incapable of winding said clockwork, a coin-controlled device for rendering said winder capable of winding said clockwork, a lock normally restraining some other machine or apparatus from operation, means connected to said winder for effecting the release of such other machine or apparatus, said coin-controlled device including a lever and arms adapted to be operatively connected thereto through the intermediary of a coin, and means for moving said arms to release said coin in proper time relation to the release of said machine or apparatus by said winder.
29. The combination with a clockwork, of a winder normally incapable of winding said clockwork, a coin-controlled device for rendering said winder capable of winding said clockwork, a lock normally restraining some other machine or apparatus from operation, means connected to said winder for effecting the release of such other machine or apparatus, said coin-controlled device in-

- cluding a lever and a pair of arms movably mounted relative to said lever, and adapted to be operatively connected thereto through the intermediary of a coin, and a cam device 5 engaged by said coin and actuated by said lever to spread said arms apart, so as to release said coin and operatively disconnect said arms from said lever.
30. The combination with a clockwork, of 10 a winder normally incapable of winding said clockwork, a coin-controlled device for rendering said winder capable of winding said clockwork, a lock normally restraining some other machine or apparatus from operation, means connected to said winder for effecting the release of such other machine or apparatus, means normally tending to actuate said lock so as to restrain said machine or apparatus from operation, said last- 15 mentioned means being normally held in restraint for a predetermined period of time measured by said clockwork, and means connected to said winder for positively overcoming the said last-mentioned means by the 20 actuation of said winder.
31. The combination with a clockwork, of 25 a winder normally incapable of winding said clockwork, a coin-controlled device for rendering said winder capable of winding said clockwork, a lock normally restraining some other machine or apparatus from operation, a latch for locking said clockwork, a lever interposed between said latch and said lock for transmitting the movement of 30 one to the other, and a cam connected to said winder to move said latch so as to enable said lock to move.
32. The combination with a clockwork having a gear, of a winder normally incapable 35 of winding said clockwork, a coin-controlled device for rendering said winder capable of winding said clockwork, said winder including a sector-gear engaging said first-mentioned gear, and said coin-con- 40 trolled device including a pair of arms operatively connected to said sector-gear, a lever normally operatively disconnected from said arms, and adapted to be operatively connected thereto through the inter- 45 intermediary of a coin, and means for operating said lever.
33. The combination with a clockwork having a gear, of a winder normally incapable 50 of winding said clockwork, a coin-con- 55 trolled device for rendering said winder capable of winding said clockwork, said winder including a sector-gear engaging said first-mentioned gear, and said coin-con- 60 trolled device including a pair of arms operatively connected to said sector-gear, a lever normally operatively disconnected from said arms, and adapted to be operatively connected thereto through the inter- 65 intermediary of a coin, means for operating said lever, said arms being movable to and from 70 each other to release the coin, and means engaged by the coin for moving said arms from each other.
34. The combination with a clockwork having a gear, of a winder normally incapable 75 of winding said clockwork, and a coin-controlled device for rendering said winder capable of winding said clockwork, said winder including a sector-gear engaging said first-mentioned gear, and said coin-con- 80 trolled device including a pair of arms operatively connected to said sector gear, a lever adapted to be connected to said pair of arms by means of a coin, means for operating said lever, said arms being movable relative to each other, and relative to said lever, and subsequently releasing said coin, and a cam device engaged by said coin and operated by said lever, adapted to intrude between said arms to spread them apart, to release said coin.
35. In a coin controlled mechanism, the combination with a shaft comprising a handle for turning it, of a sleeve rotatable thereon, arms on said sleeve, an arm fast on said shaft arranged to receive a coin, shoulders on said first arms arranged to be struck by a coin of the proper size when caught on said arm fast on the shaft and thereby cause said sleeve to revolve with said shaft as a 90 unit, a spring wound by said revolving unit, a mechanism driven by said spring, a lock for holding said mechanism normally idle, and means for releasing said lock by said revolving unit.
36. In a coin controlled mechanism, the combination with a shaft comprising a handle for turning it, of a sleeve rotatable thereon, swinging arms pivoted on said sleeve, an arm fast on said shaft arranged to receive a coin, shoulders on said first arms arranged to be struck by a coin of the proper size when caught on said arm fast on the shaft, and thereby cause said arm fast on said sleeve to revolve with said shaft as a unit, 95 mechanism controlled by said unit, and means for swinging said pivoted arms at the limit of their motion to cause them to drop the coin caught by them.
37. In a coin controlled mechanism, the combination with pivoted coin holding means, of a lock releasable upon the intervention of a coin held by said coin holding means, means for moving said coin holding means and coin into intervening position to 100 effect release of said lock, and a pivoted device engageable by a coin so held, for moving the pivoted means to effect release of said lock and to effect disengagement of the coin so held.
38. In a coin controlled mechanism, the combination with a coin carrying arm, of swinging arms adjacent to said carrying arm, shoulders on said carrying arms arranged to hold a coin on said carrying arm

- so that said arms turn as a unit, a shaft on which said carrying arm is fast, a handle for turning said shaft, a lock arranged to be released by said unit, when said carrying arm is so turned that the coin would fall except for said shoulders, and means for then swinging said swinging arms so that said coin is released and will drop from said carrying arm as said shaft returns to normal position.
39. In a device adapted normally to lock against operation some other structurally distinct machine or apparatus, in combination, two elements movable together adapted to engage and hold an object interposable between them, the first of said elements being operative to aid in effecting the release of said other machine or apparatus only when in engagement with said interposable object as aforesaid, the second of said elements being adapted to aid in releasing the device which locks against operation the said other machine or apparatus, means for moving said holding elements, and means adapted to engage said interposable object when held as aforesaid upon movement of said holding elements, whereby the second of said holding elements is made to become operative to aid in such release.
40. In a device adapted normally to lock against operation some other structurally distinct machine or apparatus, in combination, two elements movable together adapted to engage and hold an object interposable between them, the first of said elements being operative to aid in effecting the release of said other machine or apparatus only when in engagement with said interposable object as aforesaid, and the second of said elements being adapted to aid in releasing the device which locks against operation the said other machine or apparatus, means for moving said holding elements and a two-armed pivoted device one arm of which is adapted to be engaged by said interposable object held as aforesaid, and the other of which arms is thereby made to make operative in whole or in part the second of said elements to effect the release of said interposable object.
41. The combination of a mechanism, a device controlling the operation of some other machine or apparatus and normally rendering such other apparatus inoperative, said mechanism comprising two members which are operative only when engaged by an interposable member, and a third element which when actuated withdraws the device which controls the normally inoperative apparatus, means for advancing said first two members with said interposable member toward said third element, and means for presently separating said first two members so as to release said interposable member and enable one of said separated elements to get into coöperative relation with said third element to operate the latter.
42. The combination of a mechanism, a device controlling the operation of some other machine or apparatus and normally rendering such other apparatus inoperative, said mechanism comprising two members which are operative only when engaged by an interponent, and a third element which when actuated operates the device which controls the normally inoperative apparatus, means for advancing said first two members with said interponent toward said third element, and a cam device in the path of said interponent to be engaged by the latter to separate said first two members so as to release said interponent and enable one of said separated elements to get into coöperative relation with said third element to operate the latter.
43. The combination of a mechanism, a device controlling the operation of some other machine or apparatus and normally rendering such other apparatus inoperative, said mechanism comprising two levers sufficiently close to one another to be overlapped by an interponent so as to be moved together by said interponent, one of said levers being also movable with respect to the other lever to vary the distance between the levers, a third element which when actuated operates the device which controls the normally inoperative apparatus, means acting on said interponent when the latter overlaps the two levers to advance the two levers toward said third element, means which, as the levers advance together, engages the lever which is movable to vary the distance between the levers and by such engagement separates the levers, permitting said interponent to fall between the same, and bringing the lever so engaged into position to act upon and operate said third element.
44. The combination of a mechanism, a device controlling the operation of some other machine or apparatus and normally rendering such other apparatus inoperative, said mechanism comprising two levers sufficiently close to one another to be overlapped by an interponent so as to be moved together by said interponent, one of said levers being also movable with respect to the other lever to vary the distance between the levers; a third element which when actuated operates the device which controls the normally inoperative apparatus, means acting on said interponent when the latter overlaps the two levers to advance the two levers toward said third element, a cam device which, as the levers advance together, is engaged by said interponent and caused to engage the lever which is movable to vary the distance between the levers and by such engagement separates the levers, permitting said interponent to fall between the same,

and bringing the lever so engaged into position to act upon and operate said third element.

45. The combination of a mechanism, a device controlling the operation of some other machine or apparatus and normally rendering such other apparatus inoperative, said mechanism comprising two levers sufficiently close to one another to be overlapped

10 by an interponent so as to be moved together by said interponent, one of said levers being also movable with respect to the other lever to vary the distance between the levers, a third element which when actuated operates the device which controls the normally inoperative apparatus, means acting on said interponent when the latter overlaps the two levers to advance the two levers toward

15 said third element, means which, as the levers advance together, engages the lever which is movable to vary the distance between the levers, and by such engagement separates the levers, permitting said interponent to fall between the same, the lever so engaged acting upon said third element after the lever is moved to release said interponent.

46. The combination with a clockwork, of a winder normally incapable of winding said clockwork, an apparatus for rendering said winder capable of winding said clockwork, a lock normally restraining some other machine or apparatus from operation, a bell crank lever engaging said lock to operate the same, and a latch lever engaging

30 said bell crank lever to secure said bell crank lever in a position corresponding to the locked condition of said lock, said latch lever being releasable by said device, said apparatus embodying a plurality of elements operatively disconnected from each other, and adapted to be operatively connected together by an interposable member, one of

35 said elements being movable relatively to others of said elements, to release said interposable member, in proper time relation to the release of said bell crank lever by said latch lever.

47. The combination with a clockwork, of a winder normally incapable of winding said clockwork, an apparatus for rendering said winder capable of winding said clockwork, a lock normally restraining some other machine or apparatus from operation, a bell crank lever engaging said lock to operate the same, and a latch lever engaging

50 said bell crank lever to secure said bell crank lever in a position corresponding to the locked condition of said lock, said latch lever being releasable by said device, said apparatus embodying a plurality of elements operatively disconnected from each other, and adapted to be operatively connected together by an interposable member,

55 one of said elements being movable rela-

tively to others of said elements, to release said interposable member, in proper time relation to the release of said bell crank lever by said latch lever, and means for moving said elements relatively to each other to 70 release said interposable member during the movement of said winder.

48. The combination with a clockwork, of a winder normally incapable of winding said clockwork, an apparatus for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen with each other, a connection between said winder and said latch, whereby the actuation of said 85 winder will enable the movement of said latch and said lock, a spring connected to said bell crank lever normally tending to release said lock and said latch, a latch lever for preventing the movement of said bell 90 crank lever, said apparatus acting to move said latch lever to release said bell crank lever, said apparatus including a pair of arms movable relatively to each other, and said latch lever adapted to be operatively 95 connected to said pair of arms through an interposable member, and means for moving one of said arms relatively to each other to release said interposable member.

49. The combination with a clockwork, of 100 a winder normally incapable of winding said clockwork, an apparatus for rendering said winder capable of winding said clockwork,

a lock normally restraining some other machine or apparatus from operation, a latch 105 for restraining the movement of said clockwork, a bell crank lever having one arm engaging said lock and another arm engaging said latch, whereby the movement of said latch and said lock may happen with each 110 other, a connection between said winder and said latch, whereby the actuation of said winder will enable the movement of said latch and said lock, a spring connected to

said bell crank lever normally tending to release said lock and said latch, a latch lever for preventing the movement of said bell 115 crank lever, said apparatus acting to move said latch lever to release said bell crank lever, said apparatus including a pair of arms 120 movable relatively to each other, and said latch lever adapted to be operatively connected to said pair of arms through an interposable member, and means for moving one of said arms relatively to each other to 125 release said interposable member before the release of said latch lever, said last-mentioned means being operable by the movement of said arms.

50. The combination with a clockwork, of 130

- a winder normally incapable of winding said clockwork, an apparatus for rendering said winder capable of winding said clockwork, a lock normally restraining some other machine or apparatus from operation, a latch for restraining the movement of said clockwork, a bell crank lever having one arm engaging said lock and another arm engaging said latch, whereby the movement of said latch and said lock may happen with each other, a connection between said winder and said latch, whereby the action of said winder will enable the movement of said latch and said lock, a spring connected to said bell crank lever normally tending to release said lock and said latch, a latch lever for preventing the movement of said bell crank lever, said apparatus acting to move said latch lever to release said bell crank lever, said apparatus including a pair of arms movable relatively to each other, and said latch lever adapted to be operatively connected to said pair of arms through an interposable member, and a cam movable by the interposable member when held by said arms to wedge between said arms, so as to move said arms relatively to each other to release said interposable member before the release of said latch lever.
51. The combination with a clockwork, of a winder normally incapable of winding said clockwork, a device for rendering said winder capable of winding said clockwork, a lock normally restraining some other machine or apparatus from operation, and means connected to said winder for effecting the release of such other machine or apparatus, said means including a lever and a pair of arms movably mounted relatively to said lever, and adapted to be operatively connected thereto through the intermediary of an interposable member.
52. The combination with a clockwork, of a winder normally incapable of winding said clockwork, a device for rendering said winder capable of winding said clockwork, a lock normally restraining some other machine or apparatus from operation, means connected to said winder for effecting the release of such other machine or apparatus, said device including an interposable member, a lever and arms adapted to be operatively connected thereto through the intermediary of an interposable member, and means for moving said arms to release said interposable member before the release of said machine or apparatus by said winder.
53. The combination with a clockwork, of a winder normally incapable of winding said clockwork, a device for rendering said winder capable of winding said clockwork, a lock normally restraining some other machine or apparatus from operation, means connected to said winder for effecting the release of such other machine or apparatus,
- a lever and a pair of arms movably mounted relatively to said lever, and adapted to be operatively connected thereto through the intermediary of an interposable member, and a cam actuated by said interposable member when held on said lever to spread said arms apart, so as to release said interposable member and operatively disconnect said arms from said lever.
54. The combination with a clockwork having a gear, of a winder normally incapable of winding said clockwork, an apparatus for rendering said winder capable of winding said clockwork, said winder including a sector-gear engaging said first-mentioned gear, a pair of arms operatively connected to said sector-gear, a lever normally operatively disconnected from said arms, and adapted to be operatively connected thereto through the intermediary of an interposable member, and means for operating said lever.
55. The combination with a clockwork having a gear, of a winder normally incapable of winding said clockwork, an apparatus for rendering said winder capable of winding said clockwork, said winder including a sector-gear engaging said first-mentioned gear, a pair of arms operatively connected to said sector-gear, a lever normally operatively disconnected from said arms, and adapted to be operatively connected thereto through the intermediary of an interposable member, means for operating said lever, said arms being movable relatively to each other, and relatively to said lever, to subsequently release said interposable member, and means moving said arms relatively to said lever.
56. The combination with a clockwork having a gear, of a winder normally incapable of winding said clockwork, an apparatus for rendering said winder capable of winding said clockwork, said winder including a sector-gear engaging said first-mentioned gear, a pair of arms operatively connected to said sector-gear, a lever normally operatively connected thereto through the intermediary of said interposable member, means for operating said lever, said arms being movable relatively to each other, and relatively to said lever, and subsequently releasing an interposable member, and a cam operated by the movement of said arms and said lever, adapted to intrude between said arms to spread them apart, to release said interposable member.
57. The combination with a clockwork, of a winder normally incapable of winding said clockwork, a device for rendering said winder capable of winding said clockwork, a lock normally restraining some other machine or apparatus from operation, an obstructing member preventing the release of said lock, a spring normally tending to

move said obstructing member and release said lock, said obstructing member being controllable by the actuation of said winder, and a latch lever for securing said obstructing member in its locked position, said device acting to release said latch lever on the actuation of said winder.

58. The combination with a clockwork, of a winder normally incapable of winding 10 said clockwork, a device for rendering said winder capable of winding said clockwork, a lock normally restraining some other machine or apparatus from operation, an obstructing member preventing the release of 15 said lock, a spring normally tending to move said obstructing member and release said lock, said obstructing member being controllable by the actuation of said winder, and a latch lever for securing said obstructing 20 member in its locked position, normally operatively disconnected members connectible through the intermediary of an interposable member, some of said members being operatively connected to said winder, and adapted 25 to manipulate said latch lever.

59. The combination with a clockwork, of a winder normally incapable of winding said clockwork, a device for rendering said winder capable of winding said clockwork, 30 a lock normally restraining some other machine or apparatus from operation, a bell crank lever engaging said lock to operate the same, and a latch lever engaging said bell crank lever to secure said bell 35 crank lever in a position corresponding to the locked condition of said lock, said latch lever being releasable by said device.

60. The combination with a clockwork, of a winder normally incapable of winding 40 said clockwork, a device for rendering said winder capable of winding said clockwork, a lock normally restraining some other machine or apparatus from operation, a bell crank lever engaging said lock to operate 45 the same, a latch lever engaging said bell crank lever to secure said bell crank lever in a position corresponding to the locked condition of said lock, said latch lever being releasable by said device, and a signal operated by said bell crank lever to denote the 50 release of said bell crank lever by said latch lever.

61. The combination with a clockwork, of a winder normally incapable of winding 55 said clockwork, a device for rendering said winder capable of winding said clockwork, a lock normally restraining some other machine or apparatus from operation, a latch 60 for restraining the movement of said clockwork, a bell crank lever having one arm engaging said lock and another arm engaging said latch, whereby the movement of said latch and said lock may happen with each other, a connection 65 between said winder and said latch whereby the actuation of said winder will permit the movement of said latch and said lock and will remove the latch lever from its preventing position.

winder will permit the movement of said latch and said lock, a spring connected to said bell crank lever normally tending to release said lock and said latch, and a latch lever for preventing the movement of said bell 70 crank lever, said device acting to move said latch lever to release said bell crank lever.

62. The combination of an element adapted to control the operation of some operable 75 machine, a clockwork, an operating shaft, a lever on said shaft, a device secured to said shaft, a second lever loose on said shaft, means on said device and loose lever whereby they may be connected by an interponent 80 so as to move together when the shaft is rotated, means whereby said loosely mounted lever may, during the manipulation of the operating lever, be moved to release said controlling element to free the machine held 85 thereby, a locking device for normally holding the clockwork quiet, and a cam device on the shaft adapted during the operation of the operating lever to move said locking device to permit the operation of the clock- 90 work, and means whereby said clockwork when operative for a predetermined period, effects the return of said controlling element to controlling position.

63. The combination with a clockwork, 95 of a winder normally incapable of winding said clockwork, a device adapted to be rendered operable by an interponent to enable the said winder to wind said clockwork, a lock normally restraining some other machine or apparatus from operation, a latch for restraining the movement of said clockwork, a bell crank lever having one arm engaging said lock and another arm engaging 100 said latch, whereby the movement of said latch and said lock may happen with each other, and a latch lever for preventing the movement of said bell crank lever normally.

64. The combination with a clockwork, of a winder therefor, normally incapable of 110 winding said clockwork, a device adapted to be rendered capable by an interponent to enable the winder to wind said clockwork, a lock normally preventing the use of some other operable machine, a latch for restraining movement of said clockwork, a bell crank lever having one arm engaging said lock and another arm engaging said latch, whereby the movement of said latch and said lock may happen with each other, a latch 115 lever for preventing normally the movement of said bell crank lever, and a connection between said winder and said latch whereby the actuation of said winder will permit the movement of said latch and said lock 120 and will remove the latch lever from its preventing position.

65. The combination with a clockwork, of a winder normally incapable of winding said clockwork, a device adapted to be rendered 125

dered effective by an interponent, for rendering said winder capable of winding said clockwork, a lock normally restraining some operable machine from operation, a latch 5 for restraining the movement of said clockwork, a bell crank lever having one arm engaging said lock and another arm engaging said latch, whereby the movement of said lock and said latch may happen with each 10 other, a connection between said winder and said latch whereby the actuation of said winder will cause the movement of said latch and permit movement of said lock, a latch lever for preventing the movement of said 15 bell crank lever, means for releasing said latch lever, and a spring connected to said bell crank lever normally tending to release said lock.

66. The combination with a clockwork, of 20 a winder therefor, a device adapted to be rendered operable by an interponent, to enable the winder to wind said clockwork, a lock normally restraining some machine from operation, a bell crank lever having one arm 25 engaging said lock and another arm engaging said restraining device, a connection between said winder and said restraining device whereby the actuation of said winder will permit the movement of said restraining device and said lock, a latch lever for preventing movement of said bell crank lever, means connected with the winder whereby the latch lever is moved out of restraining position, and a spring connected to said 30 bell crank lever normally tending to release said lock.

67. The combination with a clockwork, of 35 a winder for said clockwork, a lock nor-

mally restraining from operation some apparatus, a latch for restraining the movement of said clockwork, a bell crank lever having an arm engaging said lock and another arm engaging said latch, whereby the movement of said lock and said latch may happen together, a connection between said winder and said latch whereby the actuation of said winder will cause the movement 40 of said latch and permit movement of said lock, and a latch lever engaging said bell crank lever in preventing the movement thereof, said latch lever adapted to be removed from said preventing position by the 45 clockwork winder.

68. The combination with a clockwork, of 50 a winder for said clockwork, a lock normally restraining some other machine from operation, a latch for restraining the movement of the clockwork, a bell crank lever having one arm engaging said lock and another arm engaging said latch, whereby the movement of said latch and said lock may happen with each other, a connection 55 between said winder and said latch, whereby the actuation of said winder will cause the movement of said latch and permit movement of lock, a spring connected to said bell crank lever normally tending to release said lock, and a latch lever for preventing the movement of said bell crank lever, said latch lever being removable from preventing position 60 by the winder.

JOHN A. MULHALL.
